TABLE LAMP

Anna Arch, New York, N. Y.

Application February 9, 1953, Serial No. 23,523

Term of patent 14 years

(Cl. D48—20)

To all whom it may concern:

Be it known that I, Anna Arch, a citizen of the United States, residing at New York, State of New York, have invented a new, original, and ornamental Design for Table Lamp, of which the following is a specification, reference being had to the accompanying drawing, forming a part hereof.

I claim:

The ornamental design for a table lamp, as shown.

ANNA ARCH.
